UNITED STATES PATENT OFFICE

ALFRED G. LEGGE, OF BROCKTON, MASSACHUSETTS

SHOE FORM

Application filed August 21, 1930. Serial No. 476,765.

This invention relates to shoe forms and has for its object the provision of a shoe form which is self adjusting to shoes having insteps of different sizes.

5 The invention will be more clearly understood from the following description in conjunction with the accompanying drawings: in which,

Fig. 1 is a sectional elevational view of a 10 shoe having inserted therein a shoe form embodying the invention;

Fig. 2 is an elevational view of the shoe form removed from the shoe; and

Fig. 3 is a plan of the same.

15 Before explaining in detail the present invention, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the claim hereto appended as considered in view of the prior art and the requirements thereof.

20 A shoe form illustrating one embodiment of the invention is shown in the accompanying drawing and comprises a toe part 10 and an instep portion comprising a lower part 11 and an upper part 12. The lower part 11 and upper part 12 of the instep portion are separated by slits 13 extending longitudinally at opposite sides of the form and each is integrally connected to the part 10. A spring 15 is connected at its opposite ends to the upper 25 and lower instep portions, as by rivets 16 and 17 respectively. A wire loop 18 is suitably connected at its ends to the lower instep portion 11 and is adapted to engage the heel of a shoe.

30 Normally, the spring 15 holds the upper and lower instep portions separated to their maximum instep size. However, if the form is inserted in a shoe 19 (Fig. 1) having an instep of smaller size, the spring 15 permits 35 the upper and lower instep portion to ad-

just themselves to the instep size of the shoe and yet holds them firmly against the interior of the shoe. The engagement of the wire loop 18 with the heel of the shoe serves to force the toe part 10 snugly into the toe part of the 55 shoe. Thus, the construction of the invention wherein the upper and lower instep portions are relatively movable renders the form self adjusting to a wide variety of shoes having different sized insteps.

40 I claim:

A shoe form comprising a toe part and an instep portion integral therewith, means permitting relative movement between the upper and lower parts of said instep portion, means 65 tending to restrain said relative movement and a heel part resiliently connected to one of said instep parts.

In testimony whereof I affix my signature.
